HOLDER FOR A MILK CARTON OR THE LIKE

Clara Virginia Eicholtz, Midland, Mich., assignor to The Dow Chemical Company, Midland, Mich., a corporation of Delaware

Filed Nov. 17, 1961, Ser. No. 67,571

Term of patent 14 years

(Cl. D44—21)

Fig. 1

Fig. 3

Fig. 4

Fig. 2

Fig. 5

Fig. 6

Fig. 7

FIGURE 1 is a side elevational view of a holder for a milk carton or the like showing my new design;

The carton shown in broken lines is for illustrative purposes only.

I claim:

The ornamental design for a holder for a milk carton or the like, as shown and described.
